ELECTRIC DETONATOR

Werner Scharwächter, Spich, Germany, assignor to Dynamit Nobel, A.G., Troisdorf, Bezirk Cologne, Germany, a German corporation

Filed July 24, 1961, Ser. No. 126,149

Claims priority, application Germany Oct. 18, 1960
2 Claims. (Cl. 102—28)

This invention relates to detonators and, particularly, to that type of detonator which is activated electrically.

Detonators as employed for setting off explosive charges are often subject to undesired ignition by stray currents, electrostatic discharges, and atmospheric electrical potential disturbances. Numerous methods and processes have been proposed to avoid such undesirable ignition and the most successful to date for such a purpose is the type which is adapted to shunt such current so that it does not affect the glow wire which is ordinarily used in the ignition circuit. Imperfections in the manufacture of such devices may render uncertain their successful operation.

It is an object of this invention to provide a construction of detonator which will positively prevent external voltage conditions from accidentally setting off the detonating charge.

Other objects and advantages of the construction will be in part obvious and in part pointed out hereinafter.

In the drawing in which is shown a prior art construction and an improved embodiment of the invention:

FIG. 1 is a longitudinal section of a detonator as found in the prior art;

FIG. 2 is a cross section taken along the line 2—2 of FIG. 1 looking in the direction of the arrows;

FIG. 3 is a longitudinal section of an improved detonator embodying the invention; and

FIG. 4 is a cross section taken along the line 4—4 of FIG. 3 looking in the direction of the arrows.

Referring to the drawing, in FIGS. 1 and 2 are shown a construction of a detonator which has found favor in the past and which is constructed with an enclosing outer housing 10 within which is suitably mounted an ignition element or glow wire 12 for igniting a detonating charge 14. Glow wire 12 is provided with a pair of conductors 16 and 18 to which is adapted to be applied a suitable electrical current from a suitable source. Glow wire 12 is attached to a pair of terminals 20 and 22 suitably mounted in a supporting body 24 held in place within housing 10. The end of housing 10 is closed by a suitable plug 26. As heretofore constructed, the support 24 is rectangular in section and the terminals 20 and 22 are spaced apart preferably symmetrical about the center of the support. Contact with the outer housing 10 is provided at opposite edges 28 and 30.

The housing 10 is normally metallic and the ordinary danger is that there will be an arc from the housing to the glow element 12, or that in some way current will pass to a terminal 20 or 22 unequally so that the difference in potential between the terminals will cause activation of element 12. In order to avoid this, in the past, the supporting element 24 has been made of conductive material of relatively high resistance so that the drop in voltage between point 28 and terminal 20 would be substantially the same as that occurring from the edge 30 to terminal 22. Thus, the effect would be an equal grounding through conductors 16 and 18 and no potential difference across the element 12. This has not always been effective, how-

2

ever, since in the process of manufacture the supporting element 24 is not always accurately made and the contact at the edges 28 and 30 with the housing 10 is not equally effective. In that case, with current passing, for instance, from the edge 28 to the terminals 20 and 22, there may well be a large potential difference at the terminals to cause glow in the element 12. Accidental discharge of the detonator may then take place.

To avoid this effect, the construction of the support for terminals 22 and 20 has been modified so that in every case the path of the currents from housing 10 to either terminal will be of substantially the same resistance. To this end, the invention provides a support 40 which in this instance, is diamond-shaped. As in the previous case, support 40 is of high-resistance material so that high voltages will not particularly obstruct the flow of current therethrough, while the ordinary low voltages used for activating the glow element 12 will not be particularly affected by shunting effect of the support. The conductors 16 and 18 are mounted at alternate corners of the support 40 which is of diamond-shape cross section and the other corners 42 and 44 are adapted to contact the wall of housing 10.

Extreme accuracy of manufacture is not essential in such a construction inasmuch as, if for instance, corner 42 is in contact with housing 10 while corner 44 is out of contact, the path electrically between corner 42 and conductor 18 will be conductively substantially the same as the path to conductor 16 and the potential at these points should be substantially the same or in any case of insufficient difference to cause any appreciable flow through element 12. The same condition will hold if corner 44 contacts the wall of housing 10 instead of corner 42. In any case, there will be no arcing from housing 10 to either conductors 16 or 18 inasmuch as the resistance through the support 40 will be less than across the gap.

Thus are accomplished, among others, the objects hereinbefore referred to.

I claim:

1. An electric detonator comprising a housing of electrically conductive material, an ignition element within the housing, a pair of electrical conductors for said element operatively connected to said ignition element and extending to without the housing, a support for said conductors of relatively low electrical conductivity mounted within the housing in contact therewith, said support supporting said conductors in spaced relation with respect to each other and with respect to the housing by engagement of the support and conductors, the shortest distance from each point of contact of the housing and support to each conductor being equal, whereby current path from said housing to each terminal is of substantially the same resistance.

2. An electric detonator as set forth in claim 1, in which said support has a diamond-shaped cross section and extends axially along said housing with one pair of opposite corners thereof contacting the housing and the other pair of opposite corners thereof spaced from the housing, one of said conductors being supported at each of said other pair of corners.
